CLAIM

The ornamental design for a microwave cooking utensil set, as shown and described.

DESCRIPTION

FIG. 1 is a first perspective view of the first element of a microwave cooking utensil set showing my new design; FIG. 2 is a second perspective view of the first element thereof;

FIG. 3 is a front view of the first element thereof;

FIG. 4 is a back view of the first element thereof;

FIG. 5 is a left side view of the first element thereof;

FIG. 6 is a right side view of the first element thereof;

FIG. 7 is a top view of the first element thereof;

FIG. 8 is a bottom view of the first element thereof;

FIG. 9 is a first perspective view of the second element of a microwave cooking utensil set showing my new design; FIG. 10 is a second perspective view of the second element thereof;

FIG. 11 is a front view of the second element thereof;

FIG. 12 is a back view of the second element thereof;

FIG. 13 is a left side view of the second element thereof;

FIG. 14 is a right side view of the second element thereof;

FIG. 15 is a top view of the second element thereof;

FIG. 16 is a bottom view of the second element thereof;

FIG. 17 is a combination view of the first element and the second element of the microwave cooking utensil set thereof; and,

FIG. 18 is an enlarged view of the selected portion 18 in FIG. 1.

The broken lines shown in the drawings depict portions of the microwave cooking utensil set that form no part of the claimed design.
